United States Patent Office.

FERDENNAND KEEFER, OF GREENFIELD, INDIANA.

Letters Patent No. 64,771, dated May 14, 1867.

HAND-PLough.

The Schedule referred to in these Letters Patent and making part of the same.

TO ALL WHOM IT MAY CONCERN:

Be it known that I, FERDENNAND KEEFER, of Greenfield, in the county of Hancock, and in the State of Indiana, have invented certain new and useful Improvements in Hand-Ploughs; and do hereby declare that the following is a full, clear, and exact description thereof, reference being had to the accompanying drawings and to the letters of reference marked thereon.

In the annexed drawings, A represents the frame of this plough, which consists of two beams placed parallel to each other, and secured from three to six inches apart by means of cross-bars which are mortised into them. B represents a wheel which is placed between the beams A A, near their rear ends, having its journal bearings in suitable boxes secured to said beams. F represents a support which projects from the under side of the beams in front of the wheel B, and which is divided at its lower end to receive between its parts a roller, G. H represents a shank, secured by a pivot or pin through its upper end between the two beams near their forward end. J represents a curved brace which runs up through an opening between the beams, and is provided with a series of holes through which a pin passes to station it at any desirable point. One end of this brace is secured to the shank H a little below its centre. The lower end of the shank is provided with a plough-point, I, which has on one side of it a flange or wing, a, which answers as a small mould-board. D represents the plough-handles, and E represents a brace the forward end of which is hinged to the upper side of the beams near their forward ends. C represents a standard which is erected upon the upper side and rear of the beams, and which passes through a mortise in the brace E.

In operating this plough, the shank H is adjusted so that its point will dip the proper depth in the earth. The operator then takes hold of the plough-handles, and placing his breast against the curved or concave end of the guide E, forces the point I through the soil. The wheel B and the roller G prevent the point I from running into the earth too deep.

Having thus fully described my invention, what I claim, and desire to secure by Letters Patent, is—

1. The arrangement of the beams A, the wheel B, roller G, and shank H, provided with the brace J and point I, as and for the purpose set forth.
2. The hinged brace E, in combination with the standard C and beams A, as and for the purpose herein specified.

In testimony that I claim the foregoing I have hereunto set my hand and seal this 12th day of March, 1867.

FERDENNAND KEEFER.
